CLAIM

The ornamental design for a lasso coupling for a merchandise display security alarm, as shown.

DESCRIPTION

FIG. 1 is a perspective view of a lasso coupling for a merchandise display security alarm showing my new design;

FIG. 2 is a front elevational view thereof;

FIG. 3 is a rear elevational view thereof;

FIG. 4 is a side elevational view thereof, the opposite side being identical in appearance;

FIG. 5 is a top plan view thereof; and

FIG. 6 is a bottom plan view thereof.

FIG. 1

FIG. 2

FIG. 4

FIG. 3

FIG. 5

FIG. 6
